UNITED STATES PATENT OFFICE.

ELISHA JESSE CADY, OF CHICAGO, ILLINOIS.

METHOD OF SATURATING PAPER-BOARD OR FELT.

1,184,070.

Specification of Letters Patent.

Patented May 23, 1916.

Application filed December 7, 1914. Serial No. 875,829.

To all whom it may concern:

Be it known that I, ELISHA JESSE CADY, a citizen of the United States, residing at Chicago, in the county of Cook and State 5 of Illinois, have invented certain new and useful Improvements in Methods of Saturating Paper-Board or Felt, of which the following is a specification, reference being had therein to the accompanying drawing.

10 My invention relates to the treatment of paperboard used in the manufacture of building paper, artificial shingles and the like, and it consists in the novel method of saturating the same with any suitable solution 15 or compound as hereinafter set forth and pointed out in the claims.

Heretofore it has been customary in saturating paper-board with liquid solutions or compounds to wind a strip or length of the 20 stock, such as strawboard or paper felt, upon a reel in a liquid bath, the stock passing into the bath as it is wound on the reel and then being left on the reel in the bath for different lengths of time ranging from 25 two to six hours according to the density of the stock to allow the liquid to soak into it, as its passage through the liquid to the reel does not do more than merely coat it. This 30 process is objectionable; when porous stock, such as paper felt, is employed the liquid is taken into the pores of the inner convolutions or windings by capillary attraction or action of the stock of the outer ones and the convolutions are not uniformly saturated as 35 the inner ones are less affected according as they lie nearer the center of the roll, while the saturation of each convolution is not uniform as its edges exposed to the liquid will become more thoroughly saturated than its 40 unexposed body, the treatment requiring two to three hours to affect the inner convolutions; when a denser material, such as straw-board for example, is used the saturation is not uniform for the same reasons, 45 while the saturation of the inner layers requires an even greater length of time as the capillary action of the denser stock is slower.

In saturating paperboard for use as building material, especially where it is to be used in places exposed to heat or the sun, uniform saturation is necessary as otherwise the product will warp, and as such warping destroys its value, the importance of eliminating this defect is apparent. By the employment of my invention I obviate this defect, besides materially reducing the cost of

manufacture and the length of time required to saturate the stock.

My invention, briefly stated, consists in immersing a roll of paperboard in a liquid solution or compound, preferably of asphalt, with the convolutions of the stock spaced apart to provide circulating space therebetween to permit the liquid to enter between the convolutions to act directly and continuously on all portions of the stock. I employ paperboard, such as strawboards, chipboards, paper felts or pulpboards for example, which is wound in the form of a roll, and a suitable spacing means is rolled up in the convolutions of the roll to hold them out of contact so that the liquid may enter between the convolutions and act directly and continuously on all portions of the surface of the stock of each convolution. The solution or compound for the bath, such as liquid asphalt, is prepared in any usual way now well known in the art for treating paperboard, and is contained in a suitable tank or vessel in such consistency that it will readily enter between the spaced convolutions of the stock in the bath and soak into the stock. The spacing means interposed between the convolutions of the stock may be of any suitable construction which will prevent contact between the succeeding convolutions and permit the solution or compound to enter between them and act with substantial uniformity on all portions of the stock, such for example as an open-mesh fabric strip, an apron formed with transversely extending bars, or a strip of woven wire fabric. The essential requisite of the spacing means is that it shall space the convolutions of the stock apart so that the liquid solution or compound of the bath may enter between them and act with substantial uniformity on all portions of the stock, and preferably I use an open-work construction so that the liquid may act directly on both sides of the stock. The strip or length of the stock with the spacing means rolled up in its convolutions is immersed in the solution or compound in the bath to allow the liquid to enter between the convolutions and in direct contact with the stock of each convolution, whereby uniform saturation is assured. This immersion may be accomplished in any suitable manner, as by preparing the roll of stock and its spacing means before immersion and then immersing the prepared unit, or, preferably, by rolling up the stock and its spacing means between

its convolutions in the bath. After being saturated with the compound or solution the stock is removed from the bath, and is subsequently treated by any suitable means according to the character of the finished product desired.

By my invention the saturation of paperboards of different degrees of density is uniform and is completed in less time than was required by the processes heretofore employed. For example, it is a fact well known and recognized by the trade that thick dense paperboards, such as straw boards, can be saturated by the methods in use prior to my invention at a maximum speed or rate of only a foot an hour, usually a foot during each hour and a half, while I have demonstrated by actual practice that by my invention uniform and thorough saturation of such heavy boards can be made on the basis of approximately a foot during a space of time varying from a minute to a minute and a half. Furthermore, the old methods required that the solid rolls of stock be immersed in the liquid asphalt of the bath for several hours in order for the capillary action of the stock to enable the liquid to evenly coat its inner convolutions, and as it was necessary to maintain the bath at a high temperature to keep the asphalt liquefied sufficiently to soak into the stock, the result was that the exposure of the stock to the high heat for such a length of time killed its fibers, whereas by my invention this defect in the product is obviated as the stock is so rapidly saturated that its fibers are not damaged. My invention enables me to use these cheaper heavy stocks for making various products, such as asphalt shingles which are now largely used, and to produce such products uniformly and thoroughly impregnated or saturated at a cheap commercial rate.

My invention may be carried out in a variety of ways, and in order to clearly illustrate the preferred manner of practising it, I represent in the accompanying drawing all the special apparatus necessary thereto, though I do not specifically claim said apparatus, which may be of any ordinary construction.

In the drawing the figure represents a sectional view of the tank or vessel containing a liquid solution or compound, preferably of asphalt, and the reels upon which a spacing apron or belt is wound.

In the drawing the reference letter A represents the tank or vessel containing the liquid asphalt solution or compound and having at its front end a roller α over which the stock is carried into the bath and at its rear a pair of rollers α' between which the stock passes from the tank. The reeling

apparatus for the interposed apron or belt here shown consists of a pair of reels B and C suitably situated in the liquid in such location that they may be freely revolved in both directions by hand or any suitable means (not shown). A flexible apron or belt D is attached at its ends to these reels so as to wind on the one while unwinding from the other, and is composed of an open-mesh textile or metallic fabric, such for example as is formed by interwoven coiled wires of small loops or turns.

In carrying out my invention the apron or belt is wound upon one of the reels as at C for example with its opposite end connected to the reel B, and the end of the length or strip of stock E is led into the bath and suitably connected to the apron or placed in the bite of the apron and the barrel of the reel B so that as the reel is revolved the stock or material is wound upon it at the same time that the apron is wound upon it with the convolutions of the apron interposed between the layers or convolutions of the stock to maintain an open space between the layers or convolutions of the latter and permit the liquid asphalt to directly attack the stock on both sides and at all points of its surface. After the reel B is thus filled the completed roll is allowed to stand until the stock is fully saturated when it may be removed by rerolling the apron or belt upon the reel C, the stock being led off between the pair of rolls α' . While the reel C is preferably located in the bath to prevent the solution from solidifying or drying on it, it may be otherwise located.

I claim:

1. The method of saturating paperstock which consists in rolling up a roll of stock with the convolutions of the stock spaced apart to provide circulating space therebetween and saturating all portions of the stock with substantial uniformity in a bath of a saturating liquid.

2. The method of saturating paperstock which consists in rolling up a length of stock in a liquid asphalt bath and rolling up a spacing apron in the convolutions of the stock to provide circulating space therebetween.

3. The method of saturating paperstock which consists in rolling up a length of stock in a liquid asphalt bath and rolling up an open-mesh apron in the convolutions of the stock to provide circulating space therebetween.

In testimony whereof I affix my signature in presence of two witnesses.

ELISHA JESSE CADY.
